UNITED STATES PATENT OFFICE

ARNO A. EWALD, OF OAKFIELD, WISCONSIN, ASSIGNOR TO ROMORT MANUFACTURING COMPANY, OF OAKFIELD, WISCONSIN, A CORPORATION OF WISCONSIN

DESIGN FOR A COMBINED ILLUMINATED INDICATOR DIAL AND CASING THEREFOR

Application filed December 9, 1931. Serial No. 42,015. Term of patent 14 years.

To all whom it may concern:

Be it known that I, ARNO A. EWALD, a citizen of the United States, residing at Oakfield, county of Fond du Lac, and State of Wisconsin, have invented a new, original, and ornamental Design for a Combined Illuminated Indicator Dial and Casing Therefor, of which the following is a specification, reference being had to the accompanying drawing, forming part thereof.

In the drawing:

Figure 1 is a perspective view of a combined illuminated indicator dial and casing therefor for a tire filling air supply station.

Figure 2 is a side elevation, partly in section, drawn to a vertical plane which includes the axis of the pointer and with a portion of one side broken away below the parts shown in section to clearly show the spaced relation

of the pointer hub to the dial, and to show the inwardly spaced relation of the dial face with respect to the outer surface of the casing or surrounding frame.

The leading features of my design are the inset circular dial plate bordered by a cylindrical light reflecting wall encircling the open space immediately in front of the dial, whereby the dial plate and its encircling annulus may have a soft shadow-free illumination derived from the sky light and from a light transmitting opening in the top portion of said cylindrical wall.

I claim:

The ornamental design for a combined illuminated indicator dial and casing therefor as shown and described.

ARNO A. EWALD.
